UNITED STATES PATENT OFFICE.

GUSTAVE NORDSTROM, OF WINNIPEG, MANITOBA, CANADA.

AUTOMATIC STEERING AND STABILIZING APPARATUS FOR AIRCRAFT.

1,264,966.

Specification of Letters Patent.

Patented May 7, 1918.

Application filed March 20, 1916. Serial No. 85,417.

To all whom it may concern:

Be it known that I, GUSTAVE NORDSTROM, a citizen of the Dominion of Canada, residing at the city of Winnipeg, in the Province of Manitoba, in the Dominion of Canada, have invented certain new and useful Improvements in Automatic Steering and Stabilizing Apparatus for Aircraft, of which the following is a specification.

10 This invention refers to steering and stabilizing apparatus and while the invention is well adapted for use in other types of aircraft I have preferred to show it in connection with a structure of aerial torpedo form, 15 as this type of vessel, carrying no passengers, is well adapted to illustrate the complete capability of the apparatus to meet all the requirements of steering and stabilizing without the necessity of human intervention.

The objects of the invention are first to provide automatic means whereby the constancy of the planes of rapidly spinning gyroscopes is made use of to maintain the 20 stability in all directions, of an aircraft; second, to provide automatic means whereby the constancy of the parallelism of the planes of the axes of a rapidly rotating gyroscope and of the earth are made use of 25 to maintain the vessel upon a predetermined direct course; third, to provide means whereby the wings of the vessel may be banked upon the taking of a curve; fourth, to provide means whereby the vessel may be 30 caused to follow various courses other than direct, such for instance as a gradually ascending spiral, or a gradually ascending or descending direct course; and fifth, to provide means whereby, upon stoppage of the 35 engine from any cause, the operation of the apparatus is immediately and automatically taken care of by other means. These and certain other objects of the invention, which will be developed as the description proceeds, I attain by the means first set out in the following specification, then particularly pointed out in the appended claims and fully illustrated in the accompanying drawings forming a part thereof, and in 40 which similar characters of reference refer to similar parts throughout the different views. In these

Figure 1 is a side elevation of an aerial torpedo partly in section to show the posi-

tions of the various parts of the apparatus, 55 in the interior thereof.

Fig. 2 is a front elevation showing the wing warping connections.

Fig. 3 is a plan view of the apparatus showing the compasses by which the course 60 of the vessel is determined.

Fig. 4 is a cross section of the interior of the vessel showing the apparatus from the front as taken on the line 4-4 in Fig. 3.

Fig. 5 is a plan view of the gyroscopic 65 apparatus taken on the line 5-5 in Fig. 4.

Fig. 6 is a sectional plan view on the line 6-6 of Fig. 4.

Fig. 7 is a front view of the electro-magnetic steering control mechanism. 70

Fig. 8 is a section of the same on the line 8-8 in Fig. 7.

Fig. 9 is a sectional view of the same on the line 9-9 in Fig. 8 and looking forward.

Fig. 10 is a profile of the mechanism used 75 to compel an ascending or descending course of the vessel.

Fig. 11 is a detail of the wing warping gearing.

Fig. 12 is a face view of one of the spiral 80 gears used to connect the wing warping connections with the power.

Fig. 13 is a view from above of the electro-magnets used to move the wing warping apparatus into operation. 85

Fig. 14 is a wiring diagram showing the circuits in which the various operative parts of the apparatus are connected.

Fig. 15 is a plan view of the electro-bar-magnets used to assist the gyroscopic apparatus to maintain the constancy of its direction. 90

In the drawings 1 indicates the body of the aerial torpedo having wings 2 of the warping-tip type. A multi-piston engine is 95 mounted in the body of the torpedo with its cylinders 3 projecting beyond the skin thereof to be air cooled.

A shaft 4 carrying a propeller 5^a at the front, extends centrally through the body 1 100 to a point just past the engine, to the piston rods of which it is crank connected in the usual manner.

A shaft 6^a is positioned in alignment with the shaft 4 and is end connected to the latter 105 for rotation normally therefrom, by a pawl and ratchet coupling 7, the ratchet wheel 8^a being secured to the engine shaft and the

pawls 9 being carried by a disk 9^a and the shaft 6^a, the pawls being held in yielding contact with the wheels by the springs 10, so that the shaft 6^a is rotated clockwise when viewed from the front. The shaft 6^a carries a pair of spaced disks 11 and 12 these having their inner faces provided with opposed spiral projections, as 13 in Fig. 12, this figure representing the disk 11, a similar projection being provided on the disk 12; a vertical shaft 14 carries a spur gear 15 the teeth on which are adapted to engage the projection on either disk as the wheel is moved toward the same, the gear wheel 15 being revolved by the engagement of its teeth with the spiral projection on the disk.

The shaft 14 projects upwardly from the torpedo and is provided at its upper end with a worm gear 16 which is constantly in mesh with the gear wheels 17 and 18 on the shafts 19 and 20 which extend out laterally and are secured to the tips 21 and 22 respectively of the left and right wings of the torpedo.

The lower end of the shaft 14 is provided with a clock-wound spring 23, the end 24 of which (Fig. 13) is secured to any suitable part of the structure, the spring serving to maintain the shaft 14 normally vertical and the gear wheel 15 out of engagement with the disks 11 and 12, the spring also serving to return the wings to their normal position after they have been warped.

The shaft 14 is further provided, immediately above the spring 23, with an armature 25, and electro-magnets 26 and 27 are positioned to actuate the armature in either direction as either may be energized, to cause the engagement of the gear wheel 15 with either the disk 11 or 12 as may be indicated.

The rear end of the body 1 is preferably tapered as shown in Fig. 1 and as is usual in such constructions, a horizontal rudder 28 being hinged at the point 29 to a suitable support 30 projecting from the end of the envelop, and a vertical rudder 31 is carried by a vertical shaft 32 stepped in a box 33 and suitably journaled for rotation at the point 34 where it passes through the envelop. The rudders conform to the usual practice in position and structure, 28 being the altitude control medium and 31 the steering medium.

The rudder operating means comprises a worm gear 35 secured upon the shaft 6^a and a series of blocks, four in number, arranged at equidistant points around the gear 35, these being normally held out of contact with the gear as will be explained herein-after, and provided on their inner faces with grooves adapted to receive the threads on the worm 35.

The vertically positioned screw blocks 36 and 37 control the altitude rudder 28, and are connected therewith by rods 38 at the

top and 39 below, through the tiller 40 on the rudder. The lateral screw blocks 41 and 42 operate the vertical rudder 31, being connected therewith by the rods 43 and 44 respectively, through the tiller 45.

The tiller rods are arranged in pairs from each block to avoid torsional strain, on the blocks.

The screw blocks 36 and 37 are carried by vertical members 46 and 47 respectively, these being provided at their outer ends with wheels 48 and 49 adapted to receive between them the tracks 50 and 51 and to travel thereon, the tracks being maintained by bolts 52 in the one case and 53 in the other, which project inwardly from the stop blocks 54 and pass slidably through openings provided for them in their respective tracks. The bolts are provided with springs 55 on each held under tension by nuts on the ends of the bolts. Similarly, the lateral screw blocks 41 and 42 (Fig. 8) are carried by members 56 and 57 provided with wheels 58 and 59 within and 60 and 61 without the tracks 62 and 63 respectively. The wheels 58 and 59 being two in number, as also the inner wheels described in the previous case, provide bracing and stability for the members to which they pertain.

The tracks 62 and 63 are maintained in a manner similar to that described for those 50 and 51, bolts 64 and 65 passing therethrough and being provided with springs 66 retained on the bolts by the nuts 67, the springs being under tension to maintain the tracks normally against the stop blocks 68 and 69.

Each of the tracks 50, 51, 62, and 63 is provided with a pair of armatures preferably positioned adjacent their ends, these being indicated as 70, 71, 72, and 73 pertaining to the tracks in the order given above.

A group of electro-magnets, four in number, is positioned at each end of the worm gear 35, these being carried on frames having hub portions 74 encircling the shaft 6^a and assisting to support the same, and arms 75 extending radially to the frame of the structure and secured thereto as shown. The members of each group of electro-magnets are mounted on bases of nonconducting material as shown at 76 in Fig. 7, whereby they are insulated from the frames on which they are mounted and from each other, and they are positioned radially so that a magnet is provided for each of the armatures carried by the rails; thus the electro-magnets 77 and 77^a, one of each group, are opposed to the armatures 70 on the rail 50; those 78 and 78^a to the armatures 71 on the rail 51; those 79 and 79^a to the armatures 72 on the rail 62, and those 80 and 80^a to the armatures 73 on the rail 63.

The members of each pair of electro-magnets are in electrical connection with each

other as shown at α and γ in Fig. 8, and it is clear that if any pair be energized the effect will be to attract the armatures associated therewith and so bring their particu-

5 lar screw block into contact with the moving worm gear 35.

81 indicates an electrical generator conveniently positioned in the body of the structure, operated by a wheel 82 in frictional 10 contact with a similar wheel 83 carried by the shaft 6^a, and 84 indicates a storage battery connected with the generator in the manner and for the purposes hereinafter explained.

15 It will be noted in Figs. 1, 3, 4 and 5, that a wall 85 is shown forming a ring around the opening into the body of the vessel, which might be closed by a cover of glass or other suitable material, the ring 85 being 20 formed from some material of good conducting properties except at the front and rear where vertical strips 86 and 87 of nonconducting material are introduced to divide the ring into two conducting zones 88 and 89 of 25 equal area, the ring itself being of course insulated from the body of the vessel.

A pair of horizontal gimbal rings 90 and 91, connected one within the other by the pivots 92 and 93, are suspended within the 30 ring 85 by the pivots 94 and 95 (at right angles to 92 and 93) which pass slidably through openings provided for them in the sides of the wall 85 adjacent the bottom thereof. The pivots 94 and 95, it will be 35 observed, are directed across the span of the vessel and they are of a length to allow of a considerable lateral movement of the gimbal rings within the wall 85, springs 96 and 97 being attached to the ring 91 and to the 40 wall of the vessel by which the said gimbal rings are held normally in central position.

A bridge 98 crosses the inner gimbal ring 90 and a central opening is provided in the bridge for the passage therethrough of a 45 vertical shaft 99, the same being carried by a ball bearing collar 100 on the bridge to provide for the free rotation of the shaft.

A disk 101 is suspended from the bottom of the shaft 99 by an arch 102 and above the 50 arch is located an electrical conducting disk 103 in electrical connection with the shaft and arch which are both conductors, as well as the disk 101, the bridge 98, however being insulated from the disk 103 by the insulating medium 104.

Above the bridge 96 an arm 105 is held by friction on the shaft 99, so that its position on the shaft may be changed by hand, the arm being hollow and having an extension 106 projecting therefrom maintained in rubbing contact with the inner periphery of ring 85 by a coiled spring 107 indicated in dotted lines in the interior of the arm (Fig. 4). A set screw 108 is provided in the arm 65 105 by means of which the extension 106

may be held firmly against the ring 85 to lock the apparatus or used to maintain the extension entirely out of contact with the ring.

109 indicates a compass card secured to 70 the shaft 99 and forming a permanent part of the apparatus, and 110 is a magnetic compass which may be removably placed on the point of the shaft 99 when it is desired to adjust the apparatus without waiting for the 75 gyroscopes to self adjust themselves.

111 indicates a gyroscope having a fly-wheel 112 mounted on a shaft or spindle 113 having its ends journaled in the lower parts 80 114 of the arch 102. 115 and 116 indicate two smaller gyroscopes having their spindles 117 and 118 suitably supported in the plane of, and at right angles to the spindle 113 of the gyroscope 111, these being provided with friction wheels 119 and 120 respectively, adapted to contact with the rear side of the fly-wheel 112 on the large gyroscope, the back of the said fly-wheel being shaped to receive them as shown in Fig. 6. Thus the gyroscopes 115 and 116 are driven 85 from the fly-wheel 112 of the gyroscope 111 and in opposite directions to each other, so that there can be no tendency toward a precessional movement on the part of these last, their sole function being to maintain the 90 horizontal plane of the disk 101 in the direction of their spindles.

The gyroscope 111 is provided with an electric motor 121 by which it is rotated counter clock wise as viewed from the side 100 on which the motor is placed, the armature and commutator 122 of the motor revolving with the spindle 113 and the field being supported from the disk 101.

The tendency of the gyroscope 111 is of 105 course to maintain the horizontal plane of the disk 101 in the opposite direction to that provided for by the gyroscopes 115 and 116 so that the constancy of the plane of the disk is assured, but the gyroscope 111 being a 110 single installation has the further tendency, as is well understood, to maintain its axis in approximate parallelism with axis of the earth, the poles of the gyroscope 111 being controlled by the direction of its rotation: 115 so that if the gyroscope 111 be rotated counter clockwise as stated or in the same direction as the rotation of the earth its poles will coincide approximately with the poles thereof and the end of the gyroscope on 120 which the motor is placed will be constantly directed toward the north.

In the diagram, Fig. 14, the shaft 6^a although not shown is being operated from the engine through the coupling 7, the dynamo 81 being driven therefrom as previously described, to supply current for the various operations of the apparatus. From the dynamo the current passes into the main circuit, this comprising a conductor 123 lead- 125

ing to a pair of switches 124 and 125 with both of which it connects, the switch 125 being adapted to contact with the point 126 in connection with the conductor 127 which 5 in turn connects with a brush 128 supported from the bridge 98 in rubbing contact with the disk 103, a good conductor, the current then passing through the shaft 99 and arch 102 into the disk 101.

10 A pair of spaced apart parallel electro-bar-magnets 129 and 130 are secured below the disk 101 by the hangers 121 pertaining to each, the planes of these being parallel with the plane of the axis 113 of the gyro- 15 scope 111, and the winding of the magnets such as to produce the poles thereof coincident with the poles of the said gyro-scope.

Thus the electromagnets assist in maintaining the parallelism of the axis of the 20 gyroscope 111 with that of the earth.

The magnets 129 and 130 are connected with the disk 101 by a conductor 132 and with the brush 133 on the motor 121 by a 25 conductor 134. The current leaves the motor by the conductor 135 and brush 136 supported from the bridge 102, which is in contact with a ring 137 secured in the gimbal ring 90 in contact with the pivots 30 92 and 93 through which it passes into the gimbal ring 91, a good conductor, thence passing out by the pivot 94 to the conductor 138. (Owing to the difficulty of showing the pivot 94 in Fig. 14, the conductor 138 35 is shown connected directly with the gimbal ring 91 in that figure, which does not of course alter the course of the current in any way.)

The conductor 138 is in constant connection with the L shaped movable arm 139 of a switch 140 through which it passes to the point 141, thence passing by the conductor 142 back to the dynamo 81 to complete the circuit.

45 The switch arm 124 previously mentioned, is adapted to contact with the point 143 connected with the conductor 144 running to the point 145 on the switch 140. The battery 84 is connected into the circuit for 50 loading purposes by the conductor 146 running to the line 144 and the conductor 147 connecting with the point 148 on the switch 140 constantly in contact with the arm 139 thereof.

55 An automatic cutout 149 is introduced into the line 144 to break connection when the battery 84 is loaded.

The switches 124 and 125 are merely a means of breaking the circuits when the apparatus is cut out of operation.

60 To operate the wing warping apparatus contact members 150 and 151 are secured rigidly to the sides of the vessel at points diametrically opposite the center of the disk 65 101, insulating material being interposed be-

tween the members and the body as at 152 in both cases. The contact members it will be noted, are shaped to engage the upper edges of the disk 101 upon a disturbance of their relation thereto.

A conductor 153 connects the contact member 150 with the electro-magnet 27 and a similar conductor 154 the contact member 151 with the electro-magnet 26, the magnets 27 and 26 being connected with the main 75 circuit wire 127 by wires 155 and 156 respectively. Thus it will be seen that as the disk 101 is freely suspended and its 80 horizontality maintained by the action of the gyroscopes, a rolling motion of the vessel 85 in counter-clockwise direction as viewed from the front, would cause the contact member 150 to engage the disk 101 thus bringing the electro-magnet 27 into circuit through the conductors 153 and 155 the 90 energy of the magnet being exerted to draw the armature 25 and shaft 14 toward it and the teeth on the spur wheel 15 into engagement with the spiral projection on the disk 12 on the shaft 6^a, which being opposed 95 to that 13 shown on the disk 11 in Fig. 12 would operate to revolve the shaft 14 clockwise as viewed from above, the worm gear 16 at the top thereof operating the gears 17 and 18 in opposite directions, that 100 17 moving clockwise as viewed from the center and warping the wing 21, through the shaft 19 upward and that 18 warping the wing 22 downward. The contact between the member 150 and the disk 101 is of course immediately broken by return of the vessel to its former position.

In like manner, should the vessel pass from the horizontal in the opposite direction the magnet 26 is energized through contact of the member 151 with the disk 101, the operations as described being duplicated through engagement of the spur gear 15 with the disk 11 on the shaft 6^a, the shaft 14 being rotated in the opposite direction this time and the operation serving to warp the wing tip 22 up, and that 21 down.

105 As previously mentioned, the gimbal ring 91 is provided with springs 96 and 97 running to the sides of the vessel, these being sufficiently under tension to maintain the gimbal ring and gyroscope apparatus suspended therefrom in central relation to the ring 85 under normal conditions: if however the vessel should take a sudden curve the springs 96 and 97 would allow of the lateral movement of the apparatus, due to centrifugal force and causing the disk 101 to contact quickly with the contact member toward which it was propelled thus bringing the warping apparatus into action to bank the plane and stabilize the movement of the vessel, the springs returning the apparatus to central position when the connection has been completed.

In the diagram, Fig. 14, the rudder control magnets in view are the rearmost member of each pair as taken on the line 14-14 in Fig. 8 so that a reference to any one of these by its indicating characters means a reference to both members of the unit of which it forms a part.

The magnets 79^a and 80^a (Fig. 14) control the rudder 31 by which the vessel is steered upon a predetermined course, the magnet 79^a being connected in circuit with the side 89 of the ring 85 by the conductor 157, and with the line 127 of the main circuit by the conductor 158. In like manner, the magnet 80^a is connected in circuit with the side 88 of the ring 85 by a conductor 159 and with the line 127 by the conductor 160.

From mention previously made, it will be understood that the gyroscopic apparatus, owing to the manner of its suspension, its free rotatability and the functions ascribed to the large gyroscope assisted by the electro-magnets 129 and 130, practically constitutes a gyro-compass having its point N constantly directed toward the north, that is to say, after a reasonable time allowance after starting, to allow it to steady itself. This being the case and if it is desired to guide the vessel upon a course due east the arm 105 is moved on the shaft 99 until it registers due east on the gyro-compass card 109, the extension 106 of the arm being placed in rubbing contact with the inner periphery of the ring 85. These adjustments are of course made while the vessel is on the ground, as that under description carries no passengers. The position of the body of the vessel when starting does not affect the steering operation. When the vessel leaves the ground, should it so happen that the extension 106 of the arm is in contact with the side 88 of the ring 85 the electro-magnet 80^a will be energized to bring the screw block 41 into engagement with the moving worm gear 35 on the shaft 6^a the rudder 31 being thereby operated to swing the nose of the vessel in a circle until the insulating strip 86 encounters the point of the extension 106, the circuit to the electro-magnet 80^a being thereby broken and the rudder released to swing back by air pressure to its neutral position, should the swing of the vessel cause the strip 86 to pass the extension 106 a circuit through the side 89 of the ring would be closed and the electro-magnet 79^a energized to operate the rudder 31 in the opposite direction through the screw block 42 and worm 35. Thus over movement of the vessel in either direction is automatically corrected and the same maintained on a direct course.

The altitude control comprises a pair of contact members 161 and 162 positioned directly in front of the disk 101 and spaced 65 apart to receive the front of the disk be-

tween them, the contacts being carried by an upright 163 and insulated from each other and the upright by the insulation 164.

The upright 163 is carried by a float 164 in a tank 165 having a faucet 166, the tank 70 165 being connected with a second tank 167 by a pipe 168 having in its length a needle valve 169, the tank 167 being positioned to deliver the liquid contained therein to the tank 165 through the pipe 168 and the valve 75 169 adapted to regulate the flow of the said liquid.

The relative position of the upright 163 to the disk 101 is maintained by a pair of radius rods 170 having their inner ends rotatably carried on the gimbal-ring supporting pins 94 and 95, and their outer ends pivotally secured to the upright 163.

The vertical member 163 may have a lateral branch 163^a to allow of the connection 85 as follows—A member 171 having the arms 172 and 173 at right angles to each other, is pivoted at the point 174 to a suitable support, a member 175 being pivoted to the offset 163^a at the point 176 and to the end 90 of the arm 172 to connect the same. A horizontal rod 177 is pivotally connected to the end of the vertical arm 173 of the member 171 and to the indicating finger 178 of an inclinometer having a vertical handle 179 95 pivoted at 180 on the shaft 181 secured to the indicating finger 178 and passing out through the side of the vessel to carry a vane 182. The handle 179 may be set at any desired point in the arc 183, and a 100 spring 184 is secured to the handle and to a clip 185 (Fig. 3) on the side of the rod 177, the spring serving to yieldingly maintain the indicating finger 178 in alinement with the handle 179. The contact 161 is 105 connected with the electro-magnet 77^a by the conductor 186, the magnet being connected with the line 127 by the conductor 187 and the contact 162 is connected with the electro-magnet 78^a by the line 188, the 110 magnet being connected with the line 127 by the conductor 189. These magnets operate similarly to those previously described with reference to the rudder 31, to bring the screw blocks 36 and 37 into engagement 115 with the moving worm 35 upon contact of the members 161 and 162 with the disk 101.

In practice, if the handle 179 be placed forward of the center of the arc 183 the contacts 161 and 162 will be depressed and the upper, 161, be closer to the disk than the lower and positioned to contact more quickly with the said disk, the adjustment of the handle regulating the amount of the incline upon which the vessel will travel, the reverse being the case if the handle be placed at the rear of the center of the arc to raise the contacts.

The vane 182 serves by air pressure to maintain the spring 184 under tension, but 130

should the nose of the craft rise to a dangerous degree bringing about a lessening of the speed of the vessel, the vane would relax pressure on the spring 184 allowing the contacts 161 and 162 to rise and the latter to contact with the under side of the disk 101 thus operating the rudder 28 downwardly to return the vessel to a level keel. Under reverse circumstances as in volplaning, the pressure on the vane 182 will increase with the increase of the speed of the vessel, thus depressing the contacts and bringing the upper of these into contact with the disk to raise the rudder 28 and check the downward incline of the vessel.

When it is desired that the vessel should travel at a gradually changing altitude, it is first started upon an upward incline by the adjustment of the handle 179, the valve 20 169 in the pipe 168 being regulated to allow liquid to pass therethrough at a predetermined rate from the tank 167 to the tank 165, as the lower tank fills the float 164 therein will rise and with it the contacts 25 161 and 162, the rising of these operating to lower the rudder 28 as previously described resulting in a change of direction on the part of the vessel from an upward incline to level and then to a downward incline.

It will be further understood that if in connection with the tank control the extension 106 of the arm 105 be made rigid against the ring 85 by means of the set screw 108, 35 the vessel may be made to describe an ascending spiral until the amount of liquid in the lower tank passes a given point after which the vessel will return on a descending spiral to the point from which it started, 40 (wind permitting) this function being mostly of value in scientific investigations.

Before starting the vessel the contacts 161 and 162 are supposed to be in raised position being maintained there by the position 45 of the end 190 of the governor 191 which engages the under side of the angularly positioned member 192 secured to the upright 163. When the engine is started the governor 191, through the expansion of its 50 springs, retracts its end 190 thus allowing the contacts 161 and 162 to descend into neutral position. This feature is of greater value in connection with aeroplanes than vessels of the torpedo type, but as the apparatus is applicable to both it is introduced.

As before stated, the shaft 6^a is rotated by a pawl and ratchet coupling 7 positive in the direction of the shaft 6^a so that the latter may be operated independently of the engine. The outer case 192 of the coupling is secured to the shaft 4 and extends around the operative parts of the coupling to carry the governor 191, the latter operating with the engine. The switch 140 comprises an immovable base 193 having uprights 194

apertured for the passage therethrough of the reduced portions 195 and 196 of the movable portion 197, the portion 196 being encircled by a spring 198 exerting its pressure to maintain the end of the portion 195 yielding against the end 190 of the governor 191.

When the engine is in operation the switch parts stand as shown by the full lines in Fig. 14, but should the engine for any reason cease to operate and the governor 191 straighten out, the switch will be thrown, the L shaped arm 139 being carried to the position shown by the dotted lines 199 and the vertical arm 200 to the position indicated by the dotted lines 201. By these movements connection between the conductors 138 and 142 is broken and connection between the lines 144 and 142 established through the arm 200 and branch 202, the 85 battery 84 being thus made a part of the main circuit and adapted to drive the dynamo 81 as a motor to continue the operation of the shaft 6^a and therethrough the various operations of the apparatus. 90

It will be noted that the straightening out of the governor operates to raise the contacts 161 and 162 thereby causing the vessel to volplane gently toward the earth.

From the foregoing description it will 95 be seen that the apparatus as described combines all the necessary features to successfully steer and stabilize air craft of the types mentioned without human intervention after starting, so that in case of a passenger carrying craft the operator would be able to devote all his attention to other matters, which might be of great importance in war time. The presence of a second person in the ship also becomes unnecessary, a point 100 105 of value in the matter of weight carried.

It will of course be understood that this specification is descriptive rather than exhaustive and that I claim as mine all such modifications of the apparatus as could 110 rightly be considered as equivalents of the features shown or as coming within the spirit of the invention or within the scope of the appended claims.

Having thus fully described my said invention, what I claim is—

1. In an air craft, the combination of stabilizing means, power means to operate the stabilizing means, electrically operated means to control the operation of the stabilizing means, contacts parallel with the longitudinal axis of the aircraft, a suspended disk in spaced relation to which the contacts are positioned, a plurality of gyroscopes arranged to maintain the constancy 125 of the plane of the disk, and means to move the contacts to change their position with reference to the disk.

2. In an air craft, the combination of stabilizing means, power means to operate 130

- the stabilizing means, electrically operated means to control the operation of the stabilizing means, contacts parallel with the longitudinal axis of the air craft, a suspended disk in spaced relation to which the contacts are positioned, a plurality of gyroscopes arranged to maintain the constancy of the plane of the disk, and air pressure operated means to automatically change the 10 position of the contacts with reference to the disk.
3. In an air craft, the combination of stabilizing means, power means to operate the stabilizing means, electrically operated means to control the operation of the stabilizing means, a suspended disk, gyroscopic means to maintain the constancy of the plane of the disk, contacts positioned above and below the disk parallel with the longitudinal axis of the air craft, tipping of the air craft causing a contact to bear against the disk to close a circuit to stabilize the air craft, and means to gradually and automatically move the contacts vertically to cause a 20 contact to bear against the disk to close a circuit to change the altitude of the air craft.
4. In an air craft, the combination of stabilizing means, power means to operate the stabilizing means, electrically operated means to control the operation of the stabilizing means, contacts parallel with the longitudinal and transverse axis of the air craft, a suspended disk in spaced relation 30 to which the contacts are positioned, gyroscopic means to maintain the constancy of the plane of the disk, means to maintain the disk normally equidistant from the transverse contacts or to yield the same into contact therewith, and means to move the longitudinal contacts in relation to the disk.
5. An air craft having an engine, a governor operated from the engine and altitude changing means operated by the governor, 40 said means comprising a horizontal rudder, power means to operate the rudder, electrically operated means to control the operation of the rudder, a suspended disk, gyroscopic means by which the constancy of the plane of the disk is maintained, contacts positioned above and below the disk parallel with the longitudinal axis of the air craft, said contacts being carried by a member having operative connection with the governor to raise or lower the contacts in accordance with the movements thereof.
6. In an air craft, the combination of steering means, power means to operate the steering means, electrically operated means 50 to control the operation of the steering means, fixed contact members on the air craft, an insulating member separating the ends of the contact members parallel with the longitudinal axis of the air craft, gyroscopic apparatus suspended adjacent the contact members, the said gyroscopic apparatus being arranged to maintain its axis approximately parallel with that of the earth and having a vertical member extending between the contact members, a radial 70 arm carried by the vertical member and movable thereon to a predetermined line of flight, the said arm having a portion adapted to contact with the insulating member in normal flight and to engage the contact 75 members upon the vessel veering from a direct course, thereby closing a circuit to operate the steering means.
7. In an air craft, the combination of steering means, power means to operate the steering means, electrically operated means to control the operation of the steering means, a pair of curved contact members positioned to form a ring and insulating strips separating the ends of the contact members 80 in parallel alinement with the longitudinal axis of the air craft; a vertical shaft normally centrally positioned with reference to the contact members and having a radial arm movable thereon to the line of flight 85 and an extension on the arm and means to maintain the extension in rubbing contact with the inner periphery of the ring; a Cardan ring from which the vertical shaft is rotatably supported and a gyroscopic unit 90 suspended from the lower end of the shaft, and means whereby the longitudinal plane of the gyroscopic unit is maintained in approximate parallelism with the axis of the earth.
8. In an air craft, the combination of steering means, power means to operate the steering means, electrically operated means to control the operation of the steering means and means to actuate the electrically 100 operated means, said last named means comprising a pair of fixed semi-circular contact members, vertical insulating strips interposed between the rear and forward ends of the contact members in parallel alinement 105 with the longitudinal axis of the air craft whereby the contacts are isolated from each other, a member suspended between the contacts, a contactor adjustably carried by the suspended member normally in rubbing contact with one of the insulating strips, gyroscopic means to maintain the horizontal plane of the suspended member, and means to maintain the constancy of the longitudinal plane of the suspended member.
9. In an air craft, the combination of steering means, power means to operate the steering means, electrically operated means to control operation of the steering means, curved contacts fixedly secured to 110 the air craft, insulating strips separating the rear and forward ends of the contacts in parallel alinement with the longitudinal axis of the air craft, a gyro-electro-magnetic 115 compass suspended below the contacts hav- 120
- 65 125 130

ing means adjustably connected therewith adapted to normally contact with one of the insulating strips and adapted to engage the contact members upon swerving of the craft 5 from a direct course to close a circuit to steer the vessel back to the direct course.

10. In an air craft, the combination of steering means, power means to operate the steering means, electrically operated means to control operation of the steering means, curved contacts laterally positioned with reference to the longitudinal axis of the air craft and having their ends approaching each other, an insulating strip 15 separating the ends of one of the contact members from those of the other, a gyro-compass suspended below the compass and having a vertical shaft projecting thereabove between the contacts, a radial arm 20 adjustable on the shaft to the line of flight and having an extension adapted for rubbing contact with the insulating strip and

contacts, and means to immovably lock the extension against one of the said contacts to steer the air craft in a circle. 25

11. In an air craft, the combination of steering and stabilizing means, electrically operated means to control the steering and stabilizing means, an engine, a shaft normally operated from the engine, a dynamo 30 driven from the shaft, means to close circuits to operate the electrically operated means from the dynamo, a storage battery loaded from the dynamo and switch means operated by stoppage of the engine to change 35 circuits to operate the dynamo from the battery.

In testimony whereof, I affix my signature in the presence of two witnesses.

GUSTAVE NORDSTROM.
